UNITED STATES PATENT OFFICE.

ORLANDO C. HARRIS, OF LOUISVILLE, KENTUCKY.

COMBINED STREET SIGN AND TRASH RECEPTACLE.

Application filed June 27, 1921. Serial No. 480,709.

To all whom it may concern:

Be it known that I, ORLANDO C. HARRIS, a citizen of the United States, residing at Louisville, in the county of Jefferson and 5 State of Kentucky, have invented certain new and useful Improvements in Combined Street Signs and Trash Receptacles, of which the following is a specification.

This invention relates to new and useful 10 improvements in combination street signs and sanitary trash receptacles, and the primary object is to provide a sanitary trash receptacle which is adapted to contain trash gathered from the streets, and which is also 15 provided with spaces for advertising or instruction signs.

A further object of the invention resides 20 in providing a support for the receptacle, the arms of which are held in place by means of a single set screw.

Still another object of the invention resides 25 in providing an improved sign construction applied to the support for the trash receptacle.

A still further object resides in constructing 30 the base of the trash receptacle in such a manner that water and other liquids may be readily drained therefrom and paper and other heavier material prevented from clogging 35 the openings through which the water is adapted to flow.

With these and other objects in view my 40 invention consists in the novel features of construction, combination and arrangement 45 of parts as will be hereinafter more fully described, illustrated and claimed.

In the accompanying drawings forming a part of this application—

Figure 1 is a perspective view of the 40 device constructed in accordance with my invention;

Fig. 2 is a vertical section therethrough;

Fig. 3 is a transverse section as seen on the line 3—3 of Fig. 2 with the trash receptacle 45 removed;

Fig. 4 is a plan view of the trash receptacle removed; and

Fig. 5 is an elevation of the main sign in 50 the spread position before it is applied to the holder.

In describing the invention I shall refer to the drawings in which similar reference characters designate corresponding parts throughout the several views, and in which 55 1 designates a base or support constructed of weighted material to retain its position

against casual displacement, the same having formed or otherwise projecting upwardly therefrom, a post or the like 2, the base being provided centrally with a 60 socket 3.

A pair of arms 4 are provided, the same having their outer ends bent upwardly as shown at 5, and their inner ends bent downwardly as shown at 6, the latter forming 65 fingers or engaging ends for reception in the socket 3. The arms 4 are disposed in diametrically opposite directions after having their ends 6 entered in the socket 3, thus forming a portion of a seat for the 70 purpose to be hereinafter described. The arms 4 are preferably formed of wire and an additional wire frame 7 of substantially 75 rectangular design is provided, the base portions 8 of which have their inner ends 75 bent downwardly to form fingers or the like 9, which are also received in the socket 3. These base portions 8 of the frame, together with the arms 4 complete the formation of the seat desired, and the fingers 6 and 9 of 80 the arms 4 and base portions 8, respectively, are secured in the socket 3 by means of a set screw 10 entering the side of the post 2, as clearly shown in Fig. 3 of the drawings.

The upper portion of the frame 7 is flared 85 outwardly as shown at 11, and the wire constituting this frame is looped upon itself at the extreme upper end to form a ring or the like 12 mounted centrally of the upper portion of the frame, as clearly shown in 90 Fig. 2 of the drawings.

The upper portion of this frame 7 and the ring 12 constitute supports for advertising or direction signs, as may be desired. A metal plate 13 is provided, the same having 95 a slot 14 centrally thereof, and this plate is adapted to be folded upon itself and applied to the upper portion of the frame 7, the slot 14 affording a means whereby the ring 12 may be passed therethrough. This 100 plate 13 may be gripped to the wire constituting the frame and forms a main sign space for the device. Advertising data or street direction may be painted or otherwise inscribed on both sides of the plate. A 105 double disk-like plate 15 is provided, the same being cut from a single sheet of metal, the two disks being connected by means of a neck or the like 16 and folded over the ring 12. Lugs or wings 17 are formed on 110 the plate 15 to be engaged with the wire constituting the ring 12, and additional

wings or lugs 18 formed thereon through the medium of which said plate 15 may be bolted as at 19 to the main sign 13. Thus, two sign spaces are provided which are bolted together and held in place on the frame. As stated heretofore, the base portions 8 of the frame 7 and the arms 4 constitute a seat adapted to receive a cylindrical receptacle 20. The receptacle 20 is for trash gathered in the streets and in order to hold the same in place the angular slotted lugs 21 are secured to the upper portion of the receptacle at diametrically opposite points thereon which receive therein the wire of the frame 7, as clearly shown in Fig. 1 of the drawings. The receptacle may be readily removed by raising the same from its seat, the flared portion 11 permitting of the disengagement of the lugs with the wire, and of course the application of the receptacle to its seat is also a simple operation.

The receptacle is provided with an annular bead 22 in its base or bottom and at regular intervals therein triangular shaped openings 23 are provided to allow water or other liquid to readily flow therefrom. These openings 23 are formed by punching outwardly the lugs or studs 24, and these triangular lugs are disposed upwardly at an angle so as to form guards against the clogging of the openings by paper or other material disposed within the receptacle.

From the foregoing description of the construction of my improved device, the operation thereof will be readily understood and it will be seen that I have provided a simple, inexpensive and efficient means for carrying out the objects of the invention.

While I have particularly described the elements best adapted to perform the functions set forth, it is obvious that various changes in the form, proportion and in the minor details of construction may be resorted to without departing from the spirit or sacrificing any of the principles of the invention.

It may be here stated that the arms 4 and the base portions 8 of the frame 7, contiguous with the fingers 6 and 9, respectively, are set in radial grooves 10', as shown clearly 50 in Figure 3 of the drawings, and through this medium the seat for the receptacle is held firmly in position for action by the set screw 10.

Having thus described my invention, 55 what I claim is:

1. A device of the character described comprising a pedestal, a substantially U shaped frame having the free ends of the arms thereof supported thereon, the crown portion of said U-shaped frame having a loop portion formed therein, a sign formed of a blank piece of metal adapted to be folded back upon itself and supported on said crown portion of said frame so as to 60 extend on opposite sides of said frame, said folded portion being provided with an elongated slot whereby said loop portion may 65 extend therethrough, and an auxiliary sign supported on opposite sides of said loop 70 portion.

2. A device of the character described comprising a pedestal, a substantially U shaped frame having the free ends of the arms thereof supported thereon, the crown 75 portion of said U-shaped frame having a loop portion formed therein, a sign formed of a blank piece of metal adapted to be folded back upon itself and supported on said crown portion of said frame so as to 80 extend on opposite sides of said frame, said folded portion being provided with an elongated slot whereby said loop portion may 85 extend therethrough, and an auxiliary sign comprising a blank piece of metal folded back upon itself adapted to be supported 90 upon said loop portion on opposite sides thereof, the free ends of said auxiliary sign extending into said slot and secured to the sides of the first mentioned sign.

In testimony whereof I affix my signature.
ORLANDO C. HARRIS.
